ORGAN ACTION

Filed Feb. 3, 1925

John T. Austin

By *J. B. Hay Lindsey* His Attorney

UNITED STATES PATENT OFFICE.

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT.

ORGAN ACTION.

Application filed February 3, 1925. Serial No. 6,512.

This invention relates to automatic musical instruments, such as organs, of the sort having note sounding devices or pipes controlled by a perforated note sheet passing over a tracker bar or equivalent element.

The aim of the invention is to provide an improved control for organs of this sort, whereby the selective association of the respective note playing ducts in the tracker bar with the several registers of note sounding devices or pipes, is brought about in a very simple and effective manner.

In accordance with the illustrative embodiment herein disclosed, the stop actions for selectively associating the note playing ducts in the tracker bar with the sounding devices or pipes of different ranks or registers are controlled by the note sheet through said note playing ducts and a master duct, the note sheet being provided with rows of note playing perforations and a row of master perforations adapted to uncover the master duct, the master perforations being so positioned with respect to certain of the perforations in the lines of note playing perforations as to effect the selective actuation of the stop actions in the desired order and at the required times. To carry out the present invention, it is only necessary to provide the tracker bar with the usual note playing ducts and with but one additional duct, here termed the master duct; and to provide the note sheet with lines of perforations corresponding in number to the note playing ducts in the tracker bar and but one additional line of perforations, herein termed the master perforations. Thus the length of the bar and the width of the perforated note sheets need be but very slightly increased. Also, by proceeding in accordance with the present invention, the various connections are reduced to a minimum, complexity is avoided, and expense is eliminated.

Other objects will be in part obvious and in part pointed out more in detail hereinafter.

The invention accordingly consists in the features of construction, combination of elements and arrangements of parts which will be exemplified in the construction hereinafter set forth, and the scope of the application of which will be indicated in the appended claims.

In the accompanying drawing, the figure diagrammatically illustrates one embodiment 55 which the features of the present invention may take, it being understood that this disclosure is by way of exemplification only, that the arrangement is susceptible of various modifications and changes, and that the 60 various parts may be modified as to mode of operation and in numbers, arrangements and positions, as desired.

In said drawing:

The figure shows a diagrammatic organization 65 partly in elevation and partly in perspective.

In order that it may be understood thoroughly that the present disclosure is by way of exemplification only; for the purpose of indicating some of the many changes and modifications which may be made; and with the object of making for conciseness and definiteness in phraseology, the following statements may be made. The term "key 75 actions" is employed for indicating those portions of the organ mechanism which, when incorporated in the ordinary manual organ, are operated from the keys (or pedals) of the keyboard, or keyboards, for 80 sounding the different notes of the sound instruments or pipes which are usually arranged in registers; while those portions of the mechanism which, when employed in the ordinary manual organ, would be operated 85 by the stop knobs, handles, tablets, or stop pedals for controlling the different "stops" or registers of pipes, are termed "stop actions." Both the "stop actions" and the "key actions" may be of any well-known 90 form and may be electric, pneumatic, or mechanical, wholly or in part, or in combination. The control of these actions through the tracker bar ducts may be effected entirely pneumatically or partly pneumatically 95 and partly electrically or mechanically. In the present instance, the "key actions" are each shown as comprising a key of a keyboard or manual and an associated operating magnet, but it will be understood, 100 as the description proceeds, that my invention may be incorporated in a musical instrument wherein, during the automatic playing of the organ, the keys are rendered inoperative, the key actions being controlled 105 by the music sheet without operating the

keys. Each of the "stop actions" is symbolically shown as comprising a draw stop and an associated operating magnet, but it is obvious that these stops may just as well be represented by tilting tablets or pedals, and that the stop actions may be controlled without operating the usual manual or pedal stop members.

Referring to the drawings in detail, 1 and 10 101 designate the respective keys of two "key actions," and 2 and 102 designate the operating magnets for these keys. The "stop actions" (only two being shown in the present instance) are illustrated as having respective draw-stops or rods 3 and 103 provided with respective operating magnets 4 and 104. In the present instance, the knobs are drawn into "on" position when the respective magnets are energized and when released are moved to "off" position as, for example, by means of the respective springs 5 and 105. As hereinafter explained more in detail, the stop action having the draw stop 3 is associated with the same duct in the tracker bar as that through which the key 1 is controlled, and the stop 103 is associated with the same duct in the tracker bar as that through which the key 101 is controlled.

30 In accordance with the present illustrative embodiment, those stops which have been moved into "on" position are latched or held in that position until another stop or combination of stops are to be brought "on," when all of the "on" stops are released. To this end I provide what, for convenience, may be termed a releasing device which may include a pivoted unit or latch A, and an operating magnet B. The latch 40 A is illustrated as having a pair of arms 6 and 106 cooperating with the armature extensions 7 and 107 depending, respectively, from the draw stops 3 and 103. The free end of the arms 6 and 106 are respectively provided with upstanding lips 8 and 108 adapted, when the magnet B is de-energized, to engage behind the extensions 7 and 107 when the draw stops are in "on" position and hold them in that position. The latch A is normally held in stop engaging position by the spring C. When the magnet B is energized, the lips 8 and 108 are lowered, whereupon the stops (or stop) which were in "on" positions are drawn by the respective springs 5 and 105, into "off" positions.

The tracker bar, over which is adapted to pass the note sheet D in the customary manner, is designated by the letter E. This note sheet is provided with rows of note playing perforations adapted to track over the usual ducts or holes in the tracker bar. In the drawings, the perforations of that row or line which control the key action, symbolized by the key 1, are designated by the numeral

9, and those perforations in the row which control the other key action, symbolized by the key 101, are designated by the numeral 109. The remaining note playing perforations are denoted by the letter F. It is, of course, understood that some of these remaining perforations may be associated with note playing ducts which, in turn, are associated with stop actions, and that others are associated with note playing ducts having no connection with a stop action. In actual practice, those note playing ducts which are associated with key actions for sounding notes or pipes most infrequently used, are employed in connection with the control of certain of the stop actions so as to avoid, as much as possible, interference with the correct rendition of the selections to be played. By way of assumption, the tracker bar may have two hundred and forty note playing ducts, and, of these, forty may be employed in connection with the control of stop actions. The ducts in the tracker bar over which the lines of perforations 9 and 109, respectively, track, are designated by the numerals 11 and 111, and the remaining ducts by the letter G. The tracker bar E, in addition to being provided with the usual note playing ducts or holes, has, preferably adjacent one end, a master duct H over which is adapted to pass a row of master perforations I which, conjointly with certain of the perforations which pass over the ducts 11 and 111, selectively control the operation of the stop actions. In the present instance, those perforations, in the row 9, which act conjointly with the perforations I to control the stop action symbolized by the draw stop 3, are designated by the numeral 12, and the perforations in the row 109, which control, conjointly with the perforations I, the stop action, symbolized by the draw stop 103, are designated by the numeral 112.

As previously stated, the control of the key actions and stop actions by the note sheet, acting through the respective tracker ducts, may be effected through instrumentalities which are wholly pneumatic or in part electric or mechanical, or otherwise. By way of exemplification, these instrumentalities which, for conciseness and definiteness in phraseology are termed "actuating devices," are in the form of pneumatically operated electric switches. The actuating means, which is individual to the key action 1, is designated generally by the numeral 13; that associated with the key 101, by the numeral 113; and that associated with the master duct H by the letter J. These actuating devices are similar in construction and, therefore, a description of one is illustrative of all. The actuating device 13, for instance, has a diaphragm or pouch 13', the space above which is connected, as shown, by the duct 11 of the tracker bar.

Below the diaphragm is an exhaust chamber K which may communicate with the space above the diaphragm through a bleed opening 13". 13" designates the resilient contact arm of a switch adapted to be thrown into engagement with a fixed contact 13"" when the duct 11 is uncovered either by a perforation 9 or a perforation 12. Corresponding parts of the actuating devices 10 J and 113 are similarly primed.

The means for changing the function of the ducts 11 and 111 and their associated actuating devices 13 and 113 (that is to say, whether they shall office as note playing or stop pulling) may take any suitable form. For example, this means may include the actuating device J controlled through the master port H, the magnet L and a gang switch arrangement M operated by the magnet L. The gang switch arrangement includes a plurality of switches corresponding in number to the number of automatically controlled stops and respectively associated with said stops and the corresponding key actions. In the present instance, the switch, associated with the actuating device 13, includes a pivoted contact member or blade 15 connected to the contact arm 13", and a pair of terminals 16 and 17 which the contact member 15 is adapted to alternately engage, these terminals being respectively connected to the key operating magnet 2 and the stop operating magnet 4. The contact member 115 of the other switch of the gang is connected to the resilient switch arm 113" and has a pair of terminals 116 and 117, respectively, connected to the magnets 102 and 104. These contact members are connected to a common armature rod N which is normally urged (when no current is passing through the magnet L) by a spring O in a direction to hold the respective members 15 and 115 in engagement with terminals 16 and 116. Arranged in series with the operating magnet L is the magnet B of the stop releasing device A, as shown by the dash line. P designates a battery which is common to the several circuits, one side of the battery being connected, as shown, to the contacts or terminals 13", 113", and J"". It may be desired, in fact, it may be preferred, to actuate the gang switch arrangement M and the stop releasing mechanism by a pneumatic or pneumatics controlled through the port H; an electrical arrangement being adapted in the showing of the drawing for convenience.

The operation of the arrangement illustrated is briefly, as follows: Assuming that all of the stops are in "off" position when the perforation 12, shown at the lower end of the note sheet, and the transversely aligned master perforation I, uncover the respective tracker bar ducts 11 and H, atmospheric

pressure will be admitted to the chamber above the diaphragm J' whereupon the contact arm J"" will be flexed to make contact with the terminal J"" causing a current to flow through the magnets B and L with the result that the releasing unit A will be drawn down to the position shown in the figure, and the armature rod N will be drawn to the left, thereby connecting the respective stop operating magnets 4 and 104 with the contact arms 13" and 113", respectively. Atmospheric pressure will also be admitted to the chamber above the diaphragm 13', whereupon the contact arm 13"" will close the circuit through the switch member 15 and the magnet 4 resulting in the energization of the latter which will thereupon pull the draw stop 3 to "on" position. The draw stop 103 will not be affected because the duct 111 is covered by the note sheet. When the note sheet has moved to such an extent that the lowermost perforation 12 and the transversely aligned master perforation I have passed the tractor ducts, atmospheric pressure to the space above the diaphragm J' is shut off, whereupon the switch of the actuating device J is broken with the result that the magnet B is de-energized, whereupon the unit A will swing up bringing the lip 8 in front of the extension 7 of the draw stop 3 to hold this draw stop in "on" position. Also, when the switch of the actuating device J is thus broken, the magnet L is de-energized, whereupon the spring O will move the gang switches to a position where the contact members engage the terminals associated with the key operating magnets 2 and 102. Now, as the perforations on that portion of the note sheet shown between the tracker ducts and the lowermost perforation 12 passed over the tracker bar, the key actions associated with these perforations were operated to sound the desired notes. For example, the lowermost perforation 9, as it passed over the duct 11, resulted in throwing the switch of the actuating device 13 "on," causing actuation of the key 1 but not affecting any of the stops. Similarly, the lowermost perforation 109 resulted in actuation of the key action symbolized by the key 101. The perforations to the right of the lowermost perforation 109 resulted in the operation of other key actions. While this group of perforations was passing over the tracker bar, the draw stop 3 was held in "on" position. When the music sheet moves to the position shown in the drawing, and in which position the ducts 111 and H are, respectively, uncovered by the first perforation 112 and the transversely aligned master perforation I, the switch of the actuating device J is again closed, whereupon the magnet B is again energized to pull the latch A down, thereby releasing the draw stop 3 from "on" to "off" position. At about the same time, 130

the magnet L is energized to throw the gang switches to the positions shown. The duct 111 being open to the atmosphere, pressure is admitted to the actuating device 113, whereupon the circuit is closed through the operating magnet 104 causing the stop 103 to be drawn to the "on" position illustrated. After the stated perforations 112 and I have passed the tracker ducts, the magnets B and 10 L are de-energized, with the result that the lip 108 will hold the stop 103 in "on" position, and the spring O will throw the gang switches into engagement with the terminals which are associated with the key operating 15 magnets 2 and 102. The following perforations will then result in the actuation of the several key actions. Certain of these perforations will result in the sounding of pipes in the register or registers other than those 20 which are sounded by preceding perforations in the same row or rows.

I claim as my invention:

1. In an automatic musical instrument, a tracker bar having a plurality of note playing ducts, a plurality of key actions respectively and normally operatively connected with said note playing ducts, a plurality of stop actions respectively associated with said note playing ducts, and means for temporarily and operatively connecting all of the stop actions with their respective note playing ducts.
2. In an automatic musical instrument, a tracker bar having a plurality of note playing ducts, a plurality of key actions respectively and normally operatively connected with said note playing ducts, a plurality of stop actions respectively associated with said note playing ducts, means for temporarily and operatively connecting all of the stop actions with their respective note playing ducts, and means for holding the actuated stop actions in operated positions between the intervals of actuation of said last mentioned means.
3. In an automatic musical instrument, a tracker bar having a plurality of note playing ducts, actuating means associated with each duct, a plurality of key actions respectively associated with said actuating means, a plurality of stop actions respectively associated with actuating means, means individual to each actuating means for alternately connecting the same to a respective key action and stop action, and means common to all of said individual means for operating the same in unison.
4. In an automatic musical instrument, a tracker bar having a plurality of note playing ducts, a note sheet passing over said tracker bars and having rows of perforations registering with said ducts, a plurality of key actions respectively controlled through said ducts, a plurality of stop actions adapted to be controlled through said ducts, and means

controlled by said note sheet for changing the character of said ducts.

5. In an automatic musical instrument, a tracker bar having a plurality of note playing ducts, a plurality of key actions respectively and normally operatively connected with said note playing ducts, a plurality of stop actions respectively associated with said note playing ducts, a note sheet having rows of perforations respectively registering with said ducts, and means controlled by said note sheet for temporarily and operatively connecting all of the stop actions with their respective note playing ducts.

6. In an automatic musical instrument, a tracker bar having a note playing duct and a master duct, a key action controlled through said note playing duct, and a stop action controlled through said ducts conjointly.

7. In an automatic musical instrument, a tracker bar having a plurality of note playing ducts and a master duct, a plurality of key actions respectively controlled through said note playing ducts, and a plurality of stop actions controlled through said respective note playing ducts conjointly with said master duct.

8. In an automatic musical instrument, a tracker bar having a plurality of note playing ducts and a master duct, a plurality of key actions respectively controlled through said note playing ducts, a plurality of stop actions also respectively controlled through said note playing ducts, and means for changing the function of said note playing ducts and controlled through said master duct.

9. In an automatic musical instrument, a tracker bar having a plurality of note playing ducts, a plurality of key actions respectively and normally operatively associated with said ducts, a plurality of stop actions associated with said ducts, and means including a single master duct in said tracker bar through which said first mentioned ducts are rendered operative to effect actuation of said stop actions.

10. In an automatic musical instrument, a tracker bar having a plurality of note playing ducts and a master duct, a plurality of key actions respectively and normally operatively connected with said note playing ducts, a plurality of stop actions adapted to be respectively and operatively connected with said note playing ducts, and means controlled by said master duct for temporarily and operatively connecting all of the stop actions with their respective note playing ducts.

11. In an automatic musical instrument, a tracker bar having a plurality of note playing ducts and a master duct, a plurality of key actions respectively and normally operatively connected with said note playing

- ducts, a plurality of stop actions adapted to be respectively and operatively connected with said note playing ducts, means controlled by said master duct for temporarily 5 and operatively connecting all of the stop actions with their respective note playing ducts, and means controlled through said master duct for latching the actuated stop actions in operated positions.
- 10 12. In an automatic musical instrument, a tracker bar having a plurality of note playing ducts and a master duct, actuated means associated with each note playing duct, a plurality of key actions respectively associated with said actuating means, a plurality of stop actions respectively associated with said actuating means, means individual to each of said actuating means for alternately connecting the same to the respective key 15 actions and stop action, and means controlled through said master duct and common to all of said individual means for operating the same in unison.
13. In an automatic musical instrument, a 20 tracker bar having a plurality of note playing ducts and a master duct, a plurality of pneumatically operated switches respectively associated with said note playing ducts, a plurality of key actions respectively associated with said switches, a plurality of stop actions also respectively associated with said switches, a gang switch for alternately connecting the pneumatic switches with their respective stop actions and key actions, and means controlled through said master duct 25 for actuating said gang switch.
14. In an automatic musical instrument, a tracker bar having a plurality of note playing ducts and a master duct, a plurality of pneumatically operated switches respectively associated with said note playing ducts, a plurality of key actions respectively associated with said switches, a plurality of stop actions also respectively associated with said 30 switches, a gang switch for alternately connecting the pneumatic switches with their respective stop actions and key actions, means controlled through said master duct for actuating said gang switch, and means controlled through said master duct for holding the actuated stop actions in "on" 35 positions between the periods of actuation of said last mentioned means.
15. In an automatic musical instrument, a tracker bar having a plurality of note playing ducts and a master duct, a note sheet having a plurality of rows of note playing perforations adapted to respectively register with said note playing ducts and a row 40 of master perforations adapted to register with said master duct, a plurality of key actions respectively controlled through said note playing ducts by said rows of note playing perforations, and a plurality of stop actions controlled through said respective note playing ducts and master duct by said master 45 perforations conjointly with certain of the perforations in said rows or note playing perforations, and means controlled by said master perforations for latching the actuated stop actions in operated positions during the periods that said master duct is 50 blanked by said note sheet.
16. In an automatic musical instrument, a tracker bar having a plurality of note playing ducts and a master duct, a note sheet having a plurality of rows of note playing perforations adapted to respectively register with said note playing ducts and a row 55 of master perforations adapted to register with said master duct, a plurality of key actions respectively controlled by said rows of note playing perforations, a plurality of stop actions adapted to be controlled by certain perforations in the respective rows of note playing perforations, and means controlled by the master perforations for changing the functions of said note playing ducts.
17. In an automatic musical instrument, a tracker bar having a plurality of note playing ducts and a master duct, a note sheet having a plurality of note playing perforations adapted to respectively register with said note playing ducts, said note sheet also having a row of ducts adapted to register with said master duct, a plurality of key actions respectively and normally operatively connected with said note playing ducts, a plurality of stop actions adapted to be respectively and operatively connected with said note playing ducts, and means controlled by said master duct for temporarily and operatively connecting all of the stop actions with their respective note playing 60 ducts.
18. In an automatic musical instrument, a tracker bar having a plurality of note playing ducts and a master duct, a note sheet having a plurality of rows of note playing perforations adapted to respectively register with said note playing ducts and a row of master perforations adapted to register with said master duct, a plurality of key actions respectively controlled through said note playing ducts by said rows of note playing perforations, a plurality of stop actions controlled through said respective note playing ducts and master duct by said master 65 perforations conjointly with certain of the perforations in said rows or note playing perforations, and means controlled by said master perforations for latching the actuated stop actions in operated positions during the periods that said master duct is blanked by said note sheet.
19. In an automatic musical instrument, a tracker bar having a plurality of note playing ducts and a master duct, a note sheet having a plurality of rows of note playing perforations adapted to respectively register with said note playing ducts and a row of master perforations adapted to register with said master duct, a plurality of key actions, actuating means respectively asso- 70 75 80 85 90 95 100 105 110 115 120 125 130

ciated with said key actions and respectively controlled through said note playing ducts by said rows of note playing perforations, a plurality of stop actions controlled through said respective note playing ducts and master duct by said master perforations jointly with certain of the perforations in said rows of note playing perforations, and

means controlled by said master perforations for latching the actuated stop actions in operated positions during the periods that said master duct is blanked by said note sheet, the actuated stop actions being released when a stop action is drawn on. 10

JOHN T. AUSTIN.
